UNITED STATES PATENT OFFICE.

DANIEL H. CHASON, OF ELIZABETH, NEW JERSEY, ASSIGNOR TO THE SINGER MANUFACTURING COMPANY, OF ELIZABETH, NEW JERSEY, A CORPORATION OF NEW JERSEY.

LOCK.

Application filed November 8, 1923. Serial No. 673,430.

This invention relates to locks, more particularly of the cabinet type, and has for an object to provide a lock of simple and sturdy construction which is inexpensive to manufacture and which is unlikely to get out of order, even after long use.

Another object of the invention is to provide the lock with means whereby the key can not be removed excepting when the parts 10 of the lock are in full locking position.

More particularly, the invention has for an object to provide a lock adapted to lock the cover member of a sewing machine carrying case to the base member with such a 15 high degree of security as to practically eliminate danger of the base element dropping away from the cover element while the machine is being carried.

Still further, the invention has for an object to provide a lock which is proof against accidental unlocking occasioned by jars, shocks or strains, such as a carrying case is apt to be subjected to.

The invention is preferably embodied in 25 a lock having a casing formed of two mating sheet-metal sections which are secured together and joined edgewise to a slotted face-plate. The casing is formed internally with slideways extending substantially parallel to 30 the face-plate. These slideways are fitted with the heads of bolts, the stems of which project through the slot in the face-plate and are oppositely and outwardly hooked to 35 provide locking shoulders. A rotary key-plate is disposed within the casing preferably between the heads of the bolts and is formed with two similar cam-slots, each entered by a corresponding follower carried by a corresponding bolt. The cam-slots 40 preferably have eccentric portions for moving the bolts into and out of locking position and concentric portions for holding the bolts securely in locking position so that any forces which may be exerted upon the bolts 45 in locking position will have no tendency to turn the cam-disk. The bolts are, by virtue of their heads, well adapted to stand heavy strains to which they are likely to be subjected when applied, say, to a sewing machine carrying case; such strains having no tendency to turn the cam-disk. The casing is 50 preferably formed with an elongated key-slot which is so related to the key-operated cam-plate that the key can be inserted or

removed only when the bolts are shot to full 55 locking position.

A better understanding of the invention may be had by referring to the accompanying drawings in which Fig. 1 is a side elevation, partly in section, of a lock embodying the invention; the bolts being in locking position. Fig. 2 is a reverse side elevation of the lock. Fig. 3 is a view similar to Fig. 1 with the front section of the casing removed. Fig. 4 is a view similar to Fig. 1 60 but with the bolts in unlocking position. Fig. 5 is a sectional view on the line 5—5, Fig. 1. Fig. 6 is a sectional view on the line 6—6, Fig. 1. Fig. 7 is a sectional view on the line 7—7, Fig. 4. Fig. 8 is a sectional view on the line 8—8, Fig. 2. Figs. 9 and 10 are perspective views of the mating casing sections. Figs. 11 and 12 are perspective 65 views of the bolt elements and Fig. 13 is a face view of the key operated cam-disk 70 which actuates the bolts.

Referring to the drawings, which illustrate the preferred embodiment of the invention, 1 represents the face-plate of the lock having a slot 2, Fig. 3, and apertures 3, 3 which are entered by the tongues 4, Figs. 9 and 10, of the similar pressed sheet-metal sections 5, 6 of the casing; said tongues 4 being upset or headed over to permanently secure the casing edgewise to the 85 face-plate 1.

The casing sections 5, 6 are each formed with a circular depression 7 and a superposed but deeper T-shaped depression constituting slideways 8 for the heads 9 of the 90 T-shaped bolts, the stems 10 of which are received in the stem portions 11 of the T-shaped depressions in the casing sections. The slideways 8 overlap one another and are parallel to the face-plate, being of substantially the same width as the heads 9 of the bolts, while the depressed portions 11 are wider than the stem portions 10 of the bolts, thereby permitting movement of the bolts in 95 their respective slideways.

The stems 10 of the bolts project exteriorly of the lock in the same direction but are oppositely and outwardly hooked at their extremities to provide the locking shoulders 12. Disposed between and in flatwise stacked relation with the bolts 9 is the circular key-operated cam-disk 13 which is received by the registering circular depres-

100

105

sions 7 and has a peripheral bearing therein confining said cam-disk in operative position.

The cam-disk 13 is formed with similar cam-slots 14 having concentric portions 15 and such slots are entered by the follower projections 16 struck up from the bolt-heads 9. The disk 13 is formed with a key-slot 17 and the bolt-heads 9 are formed with key clearance slots 18. The rear wall 6 of the casing is formed with a key clearance hole 19 and the front wall 5 is formed with a key-hole slot 20.

It will be observed that the key 21 cannot be removed from the lock except when the slot 17 is turned in register with the slot 20, under which conditions the followers 16 are in the concentric portions 15 of the cam-grooves 14 and the bolts shot to full locking position, Figs. 1, 5 and 6. When the bolts are not in full locking position, the flat key 21 is disposed at an angle to the key-hole slot 20, Figs. 4 and 7, and cannot be removed from the lock.

The casing section 6 is formed with tongues 22 and a small rounded indentation or projection 23. The tongues 22 are folded around the notched edge portions 24 of the casing section 5 to hold the sections together and the projection 23 resiliently enters either of the apertures 25, 26, in the cam-disk 13 to hold the latter in either unlocking or locking position; the wall portions of the casing between the tongues 22 being sprung enough to resiliently force the projection into said apertures.

The extremities of the bolt-stems 10 which project through the aperture 2 in the face-plate 1 are adapted to enter the usual slotted keeper-plate 27 and, when the bolts are shot, the shoulders 12 securely lock the keeper-plate 27 and face-plate 1 in superposed relation.

When applied to a portable sewing machine outfit the present lock will eliminate danger of the base-section dropping away from the cover-section as the bolts must be shot to full locking position before the key can be removed. The bolt-shifting motion transmitted from the cam-plate 13 to spread the bolt extremities is irreversible when the concentric portions 15 of the cam-slots are in engagement with the followers 16.

It will be understood that various modifications, rearrangements and reversals of parts may be made by those skilled in the art within the scope of the invention.

Having thus set forth the nature of the invention, what I claim herein is:

1. A lock comprising a slotted face-plate, a casing having internal slideways overlapping one another and disposed substantially parallel to said face-plate, a plurality of bolts having angularly related body and stem portions, said body portions being fit-

ted in overlapping relation to said slideways, the stem portions of said bolts projecting through the slot in said face-plate and having oppositely hooked extremities, and means for shifting said bolts in said slide-ways.

2. A lock comprising a slotted face-plate, a casing having internal slideways overlapping one another and disposed substantially parallel to said face-plate, a plurality of bolts having angularly related body and stem portions, said body portions being fitted in overlapping relation to said slide-ways, the stem portions of said bolts projecting through the slot in said face-plate and having oppositely hooked extremities, and a key-operated cam-plate disposed between the overlapping portions of said bolts and formed with cam-slots, said bolts each having a follower portion entering a respective cam-slot in said plate.

3. A lock comprising a slotted face-plate and casing, a pair of bolts movably mounted within said casing, said bolts at all times projecting in the same general direction through said slotted face-plate and having oppositely hooked extremities, and a slotted cam disk having a peripheral bearing within said casing and connected to move said bolts in opposite directions, the slots in said cam including eccentric bolt shifting portions and concentric bolt locking portions.

4. A lock comprising a casing, a pair of flat bolts and a flat cam-plate disposed in flatwise superposed relation within said casing, said cam-plate being positioned between said bolts, and an operative connection between said cam-plate and each of said bolts.

5. A lock having a casing comprising two mating sheet-metal half-sections each formed with a circular depression and a T-shaped depression, overlapping and deeper than said circular depression, T-shaped bolts disposed in the T-shaped depressions in the respective half-sections of the casing, and a key-operated cam-disk disposed between said bolts in the cavity formed by the circular depressions in said casing sections, said cam-disk being connected to operate said bolts.

6. A lock comprising a slotted face-plate, a casing joined edgewise to said face-plate and formed with internal slideways substantially parallel to said face-plate, a pair of T-shaped bolts having their heads disposed respectively in said slideways and their stems projecting externally of the casing through the slot in said face-plate and formed with locking shoulders, and key-operated means in said casing connected to move said bolts in opposite directions along their slideways.

7. A lock comprising a slotted face-plate, a casing formed of two mating sheet-metal halves secured together and joined edgewise to said face-plate, said casing having inter-

nal slideways disposed substantially parallel to said face-plate, a plurality of bolts fitted to said slideways within said casing and having hook portions projecting through the slot in said face-plate, and key-operated means for shifting said bolts, said last-mentioned means and the casing having registering key-slots, the key-slot in the casing permitting removal of the key only when the 10 bolts are in locking position.

8. A lock comprising a casing, a circular plate having cam-slots and a peripheral bearing within said casing, a pair of bolts mounted within said casing, one on each side 15 of said cam-plate, said bolts having followers entering said cam-slots.

9. A lock comprising a slotted face-plate

and casing, a cam-disk having a peripheral bearing within said casing, and a pair of bolts connected to be actuated by said cam-disk and having oppositely hooked portions 20 projecting exteriorly of said casing through said slotted face-plate.

10. A lock comprising a slotted face-plate and casing having an internal circular cavity, a cam-disk having a peripheral bearing within said cavity and a central key aperture, and a pair of slide-bolts actuated by and disposed on opposite sides of said cam-disk and having hooked stem portions extending through the slot in said face-plate. 25 30

In testimony whereof, I have signed my name to this specification.

DANIEL H. CHASON.
